(57) **CLAIM**

The ornamental design for a canister insert, as shown and described.

DESCRIPTION

FIG. 1 is a side elevation view of a canister insert;
FIG. 2 is a bottom plan view thereof;
FIG. 3 is a top plan view thereof;
FIG. 4 is a top perspective view thereof; and,
FIG. 5 is a top perspective view thereof with environmental matter.

The broken lines showing a canister in FIG. 5 represent environmental structure. All other broken lines illustrate portions of the canister insert. The broken lines form no part of the claimed design.
